UNITED STATES PATENT OFFICE.

PATRICK J. COSTELLO, OF CHICAGO, ILLINOIS; MARY L. COSTELLO
ADMINISTRATRIX OF SAID PATRICK J. COSTELLO, DECEASED.

CHOCOLATE-DIPPING MACHINE.

SPECIFICATION forming part of Letters Patent No. 740,811, dated October 6, 1903.

Application filed May 15, 1903. Serial No. 16,782. (No model.)

To all whom it may concern:

Be it known that I, PATRICK J. COSTELLO, a citizen of the United States, residing at Chicago, in the county of Cook and State of Illinois, have invented certain new and useful Improvements in Chocolate - Dipping Machines, of which the following is a specification.

This invention relates to a means for covering a core of candy or other material with a coating of a different substance, and refers particularly to the dipping of chocolate creams.

The primary object of my invention is to provide a machine for manufacturing coated confections—such, for instance, as chocolate creams—by means of which a plurality of holding devices each containing a number of pieces or cores of the material to be coated may be successively immersed in the coating substance and successively vibrated to remove the excess of the coating substance from the cores.

A further object of my invention is to provide a machine for manufacturing coated confections by means of which one of a plurality of holding devices containing a number of cores to be coated is immersed in the coating substance, while at the same time another holding device containing a number of cores which have been immersed in the coating substance is vibrated to remove the excess of the coating substance, whereby the capacity of the machine is increased by simultaneously subjecting to the coating process the cores contained in a plurality of holding devices.

A further object of my invention is to provide a machine of the character described which will be simple and efficient in operation and will greatly economize the cost of manufacture of coated confections.

In the embodiment herein shown of this invention a rotatable frame carries two wire baskets each having many compartments for containing individual candy cores for dipping. The rotation of the frame passes the baskets one at a time through a reservoir of liquid chocolate, and as each basket emerges from the liquid its upward movement is stopped and it is caused to vibrate longitudi-

nally to free the candies from the excess of the thick liquid chocolate which adheres to them. While one of the baskets is thus being shaken the other is inverted by the mechanism, its contents removed upon a tray by the operator, and a filled basket substituted for the empty one. 55

In the accompanying drawings, Figure 1 is a perspective view of this chocolate-dipping machine looking toward one of the rear corners thereof, showing one of the baskets as just having emerged from the chocolate-tank and the other in an inverted position, the candies having been removed therefrom. Fig. 2 is a plan view of the machine. Fig. 3 is an 60 end elevation of the machine, taken from the end shown in the foreground in Fig. 1. Fig. 4 is a transverse vertical section on dotted line 4-4 of Fig. 2 looking in the direction indicated by the arrows in said last-mentioned figure. In Fig. 4 one of the baskets and one of its supporting-arms are shown in dotted lines to illustrate the position of said basket in the liquid-chocolate receptacle. Fig. 5 is a face view of the cam G and the 65 vibrator-cam G³, also showing the vibrator-arm and a portion of one of the arms upon which it is pivotally supported. Fig. 6 is a side elevation of the vibrator-arm, showing its pivotal support, also showing the cams G 70 and G³ and the parts surrounding the outer end of the shaft E⁵ in section. Figs. 7, 8, and 9 are respectively a front elevation, a side elevation, and a plan view of one of the basket-carrying arms. Fig. 10 is a face view of 75 the cam that revolves the baskets about their supporting-shafts, holding said baskets at all times in their proper positions. Fig. 11 is a fragmental view of one of the baskets for holding the candy cores, illustrating the manner in which the basket is held by the basket-carrying arms. Fig. 12 is a view similar to that of the preceding figure, showing the basket in an inverted position and with the wooden tray for receiving the dipped candy 80 cores substituted for the wire cover of the basket. Fig. 13 is a fragmental view of the stop-wheel, the clutch, and the clutch-shaft. 90

Like letters of reference indicate corresponding parts throughout the several views. 100

In the construction of this machine I provide a main frame A, comprising the upright end members A' and A², the horizontal rods A³ for securing the end members rigidly together, and the supporting-arms A⁴ for holding the chocolate-tank in position upon the frame.

A cam A⁵ of substantially circular outline is secured rigidly to the upper portion of the upright end member A² of the supporting-frame, which cam is provided with the peripheral rim A⁶, extending nearly around the cam, with the peripheral channel A⁷, and with the channel A⁸, extending, somewhat like a chord, across an arc of the outer circle of the cam. A rack-segment A⁹ and a guide-finger A¹⁰ are fixed to the cam A⁵. Their purpose will be explained later herein. An offset A¹¹ is formed in the peripheral channel A⁷, the purpose of which offset will also be explained hereinafter.

B is a jacketed tank of semicylindrical form, its double walls providing between them a space B' for receiving steam, if it is desirable to heat the liquid chocolate within the tank, or cold water to reduce the temperature of the chocolate, if the latter is too warm.

Three stirring-screws B² of conveyer-screw form, located in the chocolate-tank and near the bottom thereof, are fixed to their rotatable supporting-shafts B³, B⁴, and B⁵, which shafts extend through suitable stuffing-boxes B⁶ in one end of said tank B and bear at their outer ends the three sprocket-wheels B⁷, B⁸, and B⁹, respectively. The shaft B³ carries the tight and the loose pulleys B¹⁰ and B¹¹, respectively, over the former of which a belt is intended to be passed from an independent counter-shaft (not shown) to drive the screws B² for stirring the chocolate within the tank B. An endless chain belt B¹² passes around the two outside sprocket-wheels B⁷ and B⁹ and over the top of the sprocket-wheel B⁸, the proper tension of said chain belt being maintained by the pivoted arm B¹³, carrying the idler-pulley B¹⁴ at its free end and supported by the adjustable tension-spring B¹⁵. The movement of the endless chain belt B¹² about and over the sprocket-wheels B⁷, B⁸, and B⁹ causes the two outer screws within the tank B to rotate in the same direction and the middle screw to rotate in a contrary direction.

C is a drive-shaft rotatably mounted in suitable bearings in the upright members A' and A² of the supporting-frame A. This shaft C carries near one of its outer ends the drive-pulley C', adapted to receive a belt passing from a counter-shaft (not shown) to communicate motion to the mechanism. The shaft C is constantly driven throughout the operation of the machine. A pulley C² is fixed to the shaft C within the supporting-frame A, and a belt C³, passing upward from said pulley, communicates motion for driving the mechanism which vibrates the basket of freshly-dipped chocolate in order to shake the

excess of liquid chocolate from the cores, which vibrating mechanism will be later described herein.

C⁴ is a sprocket-wheel fixed on the shaft C, over which wheel the chain belt C⁵ is adapted to run. The chain belt C⁵ is provided with a tightener-arm C⁶, loosely mounted on the shaft C. This arm carries at its outer end the idler-pulley C⁷, adapted to engage the belt C⁵, and a tension-spring C⁸ holds said idler-pulley C⁷ against said belt C⁵.

A clutch-shaft D is journaled in suitable bearings in the lower part of the supporting-frame A. It is provided with the sprocket-wheel D', loosely mounted on the shaft D, carrying one (the free) member of the clutch mechanism. D² is a collar having a sliding engagement with the shaft D, but rotatably secured thereto and adapted to carry the other member of the clutch mechanism. This clutch mechanism may be of any suitable form.

D³ is an L-shaped lever for sliding the clutch-collar D² lengthwise of the shaft D. This lever is pivotally mounted upon the bolt D⁴ on the member A' of the supporting-frame A and is in yoke form at its upper end to surround the clutch-collar D². The opposite end of the L-shaped lever D³ extends within the supporting-frame A and rests upon the inner end of the foot-lever D⁵, which foot-lever is pivotally mounted at D⁶ upon one of the horizontal rods A³, its forward end projecting within convenient reach of the operator's foot. It will thus be seen that when the foot-lever D⁵ is depressed by the foot of the operator the clutch-collar D² throws the clutch mechanism rotatably fixed to the shaft D into frictional engagement with the constantly-rotating clutch member carried by the sprocket-wheel D', rotating the shaft D as long as said clutch-collar is held in engagement with the free member of the clutch. At the opposite end of the shaft D is fixed a sprocket-wheel D⁷, carrying the endless chain belt D⁸.

E is the main shaft, journaled in suitable bearings, one in the center of the cam A⁵ and the other in the upper end of the upright member A' of the supporting-frame A. The shaft E carries the two arms E' and E², rigidly fixed to said shaft within the supporting-frame A. The outer ends of the arms E' and E² are provided with the enlarged bosses E³ and E⁴, respectively, and within said bosses are journaled the two shafts E⁵. The arm E² is provided at each side of the shaft with two outwardly-extending perforated ears E⁶, between which the vibrator-arms, to be later described herein, are pivotally mounted.

A stop-wheel E⁷ is fixed to the shaft E just outside the supporting-frame A. This stop-wheel E⁷ is provided on its periphery, on opposite sides thereof, with the three projections E⁸, E⁹, and E¹⁰. An arm E¹¹, having in its upper end a roller E¹² for engaging the periphery of the stop-wheel E⁷, is mounted upon

the shaft E¹³, journaled in the member A' of the supporting-frame A. This arm is held so that the roller E¹² is in contact with the periphery of the stop-wheel E⁷ by the helical spring E¹⁴, extending between the arm E¹¹ and a fixed portion of the supporting-frame A. The shaft E¹³ also carries the downwardly-extending arm E¹⁵, having the hook E¹⁶ for engaging the under side of the L-shaped lever

D⁸. When the foot-lever is depressed and the L-shaped lever D⁸ thereby raised, the hook E¹⁶ of the arm E¹⁵ is caused by the spring E¹⁴ to engage and hold elevated the L-shaped lever D⁸, whereby the clutch mechanism is held in clutch. As long as the two members of the clutch mechanism are engaged the shaft D rotates, driving the shaft E by means of the endless chain belt D⁸. As soon, however, as one of the projections E⁸, E⁹, and E¹⁰ comes in contact with the roller E¹² of the arm E¹¹ said arm is moved outward against the tension of the spring E¹⁴, rocking the shaft E¹³ in its bearings and withdrawing the hook E¹⁶ of the arm E¹⁵ from its engagement with the L-shaped lever D⁸, permitting said lever to fall of its own weight and the members of the clutch to be disengaged, thus automatically stopping the rotation of the shaft E.

E¹⁷ and E¹⁸ each represent two pins set at diametrically opposite points on the side of the stop-wheel E⁷, and a stop-arm E¹⁹, adapted to engage said pins as the stop-wheel rotates, prevents a backward movement of the shaft E. A spring E²⁰ holds said stop-arm E¹⁹ in a position to be engaged by said pins E¹⁷ and E¹⁸.

Motion is imparted to the shaft E from the shaft D by means of the endless chain belt D⁸, passing over the sprocket-wheel D⁷, fixed on the shaft D, and the sprocket-wheel E²¹, fixed on the shaft E.

Two basket-carrying arms F, similar in their construction, are rigidly mounted upon each of the shafts E⁵, and the baskets which they are intended to support are counterbalanced by the weights F', also fixed on each of said shafts E⁵ and extending in the contrary direction from the arms F. The arms F are bifurcated at their outer ends and are provided with the stop-pins F² and the spring-actuated holding-jaws F³ for grasping the handles of the baskets, to be later described, the upward movement of the baskets being limited by said stop-pins and their downward displacement by the holding-jaws F³. A spring-jaw F⁴ is adapted to hold in place the tray for receiving the chocolates after the same have been dipped, which tray will be more fully described later herein. A thumb-lever F⁵, pivotally mounted one on each of the arms F, is intended to withdraw the spring-jaws F⁴ from engagement with the tray when it is desirable to remove the latter from the machine.

G is a cam fixed to the member A' of the supporting-frame A by means of the hood and integral sleeve G'. Within this hood G'

a pulley G² is loosely mounted on the shaft E, and this pulley is adapted to be constantly rotated by the crossed belt C³, which also extends over the face of the pulley C². A wave-shaped cam G³ is formed integral with the pulley G² and is therefore constantly rotated therewith. Each of the shafts E⁵ at its end adjacent to the boss E⁴ is provided with a sleeve G⁴, fixed on said shaft. This sleeve G⁴ is provided at its outer end with an enlarged head portion G⁵, and this head portion has two upwardly-extending perforated ears G⁶. The boss E⁴ is bored out to a diameter to correspond to that of the head portion G⁵ of the sleeve G⁴ throughout the greater portion of its length; but at its inner side an opening is left corresponding in size to the diameter of said sleeve G⁴. Within the annular space in said boss surrounding said sleeve G⁴ is provided a helical spring G⁷, the tendency of which is to slide the shaft E⁵ endwise in its bore in an outward direction. An adjusting-nut G⁸, threaded upon the sleeve G⁴, limits the outward movement of the shaft E⁵, and a milled locking-collar G⁹, also threaded on said sleeve, holds said adjusting-nut in any desired position. A collar G¹⁰ is fixed to the shaft E⁵ within the flange of the locking-collar G⁹.

G¹¹ is a vibratory arm pivotally mounted near its center upon the bolt G¹² and having at its rear end an elongated opening G¹³, adapted to receive the pin G¹⁴, extending through the perforated ears G⁶ of the head portion G⁵ of the sleeve G⁴. The forward end of the arm G¹¹ is provided with a conical roller G¹⁵, adapted to be engaged by the wave face of the cam G³, also at certain portions of its revolution with the shaft E to bear against the cam G and be raised by said cam from engagement with the wave surface of the wave cam G³. It will be noticed that the high portion of the cam G occupies about two-thirds of its peripheral surface and is at the upper and the forward side of the machine and at a point beneath the shaft E, it not being desirable to vibrate the shafts E⁵ while the baskets are being inserted and while they are being passed through the liquid chocolate. When the baskets emerge from the chocolate, the cam-surface G permits the conical roller G¹⁵ to be depressed sufficiently to engage the wave surface of the cam G³. When the roller G¹⁵ is in engagement with said cam G³, the shaft E⁵ is rapidly vibrated in a longitudinal direction, the raised portions of the wave surface of the cam G³ throwing said shaft inward and compressing the helical spring G⁷, which immediately throws the shaft in the contrary direction, as the conical roller G¹⁵ coincides with a depression in the cam G³.

H is a pinion fixed on the inner end of each of the shafts E⁵. It is adapted to engage the rack-segment A⁹, which latter is of such a length as to impart one complete rotation to said shaft E⁵. Outside of the pinion H each

of the shafts E⁵ bears a hub H', also fixed to its shaft, which hub is provided with two radially-extending arms H² and H³, bearing at their outer ends the rollers H⁴ and H⁵, respectively. The arm H² has the upwardly-extending stud H⁶, adapted to be engaged by the guide-finger A¹⁰, and thereby be held in proper position at the point in its revolution about the cam when the pinion is just coming into mesh with the rack-segment A⁹ to insure the registration of the proper tooth of the pinion with the first tooth in the segment.

I is a chocolate-basket having the rectangular marginal frame I' and the longitudinal and the transverse cross-wires I², formed into loop-shaped receptacles each for containing a single core of the chocolate drops. Outwardly-extending handles I³, adapted to be grasped by the spring-actuated jaws F³ and be held in the outer bifurcated ends of the arms F, are secured rigidly to the rectangular frame I' at opposite ends thereof.

I⁴ is a wire cover adapted to be secured in any convenient manner over the top of the basket I in order to hold the cores for the chocolate drops in position in their individual receptacles in the baskets I. I have employed the spring-hooks I⁵ for engaging the sides of the marginal frame I'; but any suitable means may be employed for holding the cover I⁴ in position.

I⁶ is a tray adapted to lie between the arms F over the basket I and be held in position by the spring-jaws F⁴ after the wire cover has been removed from the basket. The wire cover I⁴ is removed and the tray I⁶ put in place over the basket I while the latter is in an upright position, and the tray is withdrawn after the basket has been inverted and the chocolate drops turned out upon it.

J represents openings for the admission of steam or water to the jacket of the chocolate-tank B and for the escape of said steam or water therefrom.

In the operation of this machine power is communicated by belt passing from suitable counter-shafts to the drive-pulley C' and the tight and the loose pulleys B¹⁰ and B¹¹, respectively. Liquid chocolate is placed within the jacketed tank B, is stirred therein by the rotating screws B², and is kept at the proper temperature by the admission of steam or cold water into the space B' between the double walls of said tank. The cores or candy to be dipped are placed within the baskets I, the wire covers I⁴ of said baskets are secured in position, and the whole placed between the carrying-arms F, the wire handles I⁸ of said baskets being grasped by the spring-actuated jaws F³ of said arms. The foot-lever D⁵ is depressed by the operator, causing the clutch-collar D² to throw the clutch mechanism rotatably fixed to the shaft D into frictional engagement with the constantly-rotating clutch member carried by the sprocket-wheel D'. The motion thus imparted to the shaft D is transmitted by the endless chain belt D⁸ to

the shaft E, causing said shaft to rotate and to dip the basket I into the chocolate-tank, passing it through the liquid chocolate in said tank. As the basket I emerges from the liquid in the tank B the conical roller G¹⁵ of the vibrator-arm G¹¹ is permitted by the conformation of the cam G to engage the wave surface of the cam G³, which irregular surface moves said arm in one direction upon its pivot G¹², thrusting the shaft E⁵ endwise in its bearings against the action of the helical spring G⁷, which spring throws the shaft in the opposite direction as each depression in the wave surface of the cam G³ coincides with the conical roller G¹⁵. Inasmuch as the cam G³ rotates with a considerable velocity, the end vibration of the shaft E⁵ is quite rapid and sufficiently violent to shake the excess of liquid chocolate from the dipped candies, the quantity of chocolate remaining upon the cores being regulated by the duration of the vibratory movement.

The projection E⁸ on the stop-wheel E⁷ causes the mechanism to stop, first, when the lower basket is in the middle of the tank B; second, when it has just risen above the tank, and, third, after it has assumed a horizontal position and has been lifted a little distance above the top of the tank B. The lower basket I continues in a position tangent to the circumference of the circle described by its revolution until the roller H⁴ engages the offset A¹¹ of the peripheral channel A⁷ in the cam A⁵. When this occurs, the roller H⁵ is at the end of the chordal channel A⁸, and as the first-mentioned roller H⁴ is retarded the second roller H⁵ passes upward in said channel A⁸ until the basket assumes a horizontal position. The direction of the channel A⁸ changes slightly at this point, and the roller H⁴ clears the offset A¹¹ in the cam A⁵, and the rollers proceed side by side, the relative directions of the outer channel and the chordal channel of the cam A⁵ being adapted to retain said basket in a horizontal position. When the supporting-arms E' and E² assume a vertical position, one of the stop projections E⁸ engages the roller E¹² of the arm E¹¹, pushing said arm outward against the action of the spring E¹⁴ and withdrawing the hook E¹⁶ of the arm E¹⁵ from its supporting engagement with the L-shaped lever D³, permitting that lever to fall of its own weight and the clutch mechanism to become disengaged, stopping the rotation of the shaft D, and consequently that of the shaft E. The first basket is now in its uppermost position, and if a second basket has been placed between the second pair of basket-carrying arms F the last-mentioned basket is in its lowest position in the center of the tank B, both baskets being upright. The operator at this point removes the wire cover I⁴ from the top of the upper basket I and puts in its place the tray I⁶, starting the machinery again by depressing the foot-lever D⁵. The rollers H⁴ and H⁵ are directed downward by the peripheral rim A⁶.

of the cam A⁵, the guide-finger A¹⁰ engaging the stud H⁶ on the arm H² to prevent the roller H⁴ from passing away from the center of the cam and to direct the pinion H into engagement with the rack-segment A⁹ in its proper relation thereto. The pinion H, meshing with the segment A⁹, causes the shaft E⁵ to be rotated and the basket I to revolve about said shaft. The stop projection E⁹ on the stop-wheel E⁷ engages the roller E¹² on the rim E¹¹ and stops the mechanism just as the basket is inverted directly over its shaft E⁵. The operator now presses the thumb-lever F⁵ and withdraws the tray H⁶ from the face of the inverted basket, the chocolates having dropped out of the depressions in said basket onto the tray. Again depressing the foot-lever D⁵, the mechanism is started in motion, the shaft E⁵ continues its rotation, and the basket I is revolved to an upright position directly beneath said shaft E⁵, where the mechanism is again stopped by the engagement of the projection E¹⁰ with the roller E¹² of the arm E¹¹ and the consequent disengagement of the clutch members. At this point the empty basket is removed from the carrying-arms F and a filled basket with a wire cover I⁴ in place substituted for the empty one. The cycle of movement is again commenced, the basket I is tilted downward, entering the tank B in an inclined position, it standing at a tangent with the circumference of the circle described by its revolution. When the basket just inserted reaches the lowest position in the tank, the mechanism again stops, the other basket having attained its highest place, where the wire cover I⁴ is removed and the wooden tray I⁶ is put in place. The mechanism being again started, the lower basket moves upward, emerging from the liquid chocolate in an inclined position, and when reaching a point about even with the top of the tank its forward movement is checked and its vibration commenced. The opposite basket at this point is in its inverted position and the chocolates are being removed upon the tray I⁶ by the operator. After again starting the mechanism the next stop of the basket is when it has again assumed a horizontal position, its vibratory movement still continuing. It stands in this position, having the excess of liquid chocolate shaken from the candies within the basket I, until the opposite empty basket has been removed and another filled one put in its place.

The cam G is fixed in its relation with the supporting-frame A. Its cam-surface is of such form that the conical roller G¹⁵ is raised from engagement with the wave surface of the cam G⁸ excepting for about one-third of a revolution of the shaft E. The cam G⁸ is constantly revolved. This is also true of the drive-shaft C, the drive-pulley C', and the sprocket-wheel D', which carries the free member of the clutch mechanism; also of the shafts B³, B⁴, and B⁵, carrying the screws B² for stirring the liquid chocolate in the tank B.

From the foregoing description it will be observed that I have invented a machine for manufacturing coated confections by means of which a plurality of holding devices each containing a large number of cores are successively immersed in the coating substance and subsequently successively vibrated, thereby giving to the machine a large capacity or output, inasmuch as while one holding device is being immersed another holding device is subjected to a vibratory movement to remove the excess of the coating substance.

While I have described more or less precisely the details of construction, I do not wish to be understood as limiting myself thereto, as I contemplate changes in form, the proportion of parts, and the substitution of equivalents, as circumstances may suggest or render expedient, without departing from the spirit of my invention.

I claim as my invention—

1. In a chocolate-dipping machine, in combination, a supporting-frame; a receptacle for the liquid chocolate; a rotatable shaft journaled on said frame; a basket for containing the candy cores to be dipped, supported by said shaft; means for rotating said shaft and passing the cores within said open receptacle beneath the surface of the liquid chocolate; and means for continuously vibrating said open receptacle during a portion of the cycle of its movement to remove the excess of chocolate from said cores.

2. In a chocolate-dipping machine, in combination, a supporting-frame; a receptacle for the liquid chocolate; a shaft rotatably mounted on said frame; a basket for containing the candy cores to be dipped, supported by said shaft; means for rotating said shaft and passing the cores within said basket beneath the surface of the liquid chocolate; and a cam for continuously vibrating said basket during a portion of the cycle of its movement to remove the excess of chocolate from said cores.

3. In a chocolate-dipping machine, in combination, a supporting-frame; a receptacle for the liquid chocolate; a shaft rotatably mounted on said supporting-frame; an arm fixed on said shaft; a basket for containing the candy cores to be dipped, pivotally supported on said arm; means for rotating said shaft to pass the candy cores beneath the surface of the liquid chocolate; and a cam for continuously vibrating said basket during a portion of the cycle of its movement to remove the excess of chocolate from said cores.

4. In a chocolate-dipping machine, in combination, a supporting-frame; a receptacle for the liquid chocolate; a shaft rotatably mounted on said frame; two arms fixed on said shaft; a basket for containing the candy cores to be dipped, pivotally supported between said arms; means for rotating said shaft to pass the cores within said basket beneath the surface of the liquid chocolate;

and a cam for continuously vibrating said baskets during a portion of the cycle of their movement to remove the excess of chocolate from said cores.

5. In a chocolate-dipping machine, in combination, a supporting-frame; a receptacle for the liquid chocolate; a main shaft rotatably mounted on said frame; two arms fixed on said shaft; a shaft journaled near the outer ends 10 of said arms; a basket for containing the candy cores to be dipped, supported by said last-mentioned shaft; means for rotating the main shaft to pass the cores within the basket beneath the surface of the liquid chocolate; and a cam for longitudinally vibrating 15 the basket-supporting shaft during a portion of the cycle of its movement, for removing the excess of chocolate from said cores.

6. In a chocolate-dipping machine, in combination, a supporting-frame; a receptacle for the liquid chocolate; a main shaft rotatably mounted on said frame; an arm fixed on said main shaft; a basket for containing the candy cores to be dipped, pivotally supported on said 25 arm; means for rotating said main shaft to pass the candy cores beneath the surface of the liquid chocolate; and a cam for causing said basket to revolve about its pivotal support.

30 7. In a chocolate-dipping machine, in combination, a supporting-frame; a receptacle for the liquid chocolate; a main shaft rotatably mounted on said supporting-frame; an arm fixed on said shaft; a basket for containing 35 the candy cores to be dipped, pivotally supported on said arm; means for rotating said shaft to pass the cores beneath the surface of the liquid chocolate; a cam for causing said basket to revolve about its pivotal support; 40 and a stud fixed with relation to said basket, for engaging with said cam.

8. In a chocolate-dipping machine, in combination, a supporting-frame; a receptacle for the liquid chocolate; a main shaft rotatably 45 mounted on said supporting-frame; an arm fixed on said shaft; a shaft journaled in said arm; a basket for containing the candy cores to be dipped, fixed with relation to said last-mentioned shaft; a cam for rotating said shaft 50 as it is caused to revolve about the main shaft; and a stud on said shaft for engaging said cam.

9. In a chocolate-dipping machine, in combination, a supporting-frame; a receptacle for the liquid chocolate; a main shaft rotatably 55 mounted on said supporting-frame; an arm fixed on said shaft; a shaft journaled in said arm; a basket for containing the candy cores to be dipped, fixed with relation to said last-mentioned shaft; means for rotating said 60 main shaft to pass the candy cores beneath the surface of the liquid chocolate; a cam fixed with relation to said supporting-frame, said cam having a peripheral rim and a peripheral and a chordal channel; and two studs 65 fixed with relation to the basket-supporting shaft, for engaging said cam.

10. In a chocolate-dipping machine, in combination, a supporting-frame; a receptacle for the liquid chocolate; a main shaft rotatably mounted on said supporting-frame; two arms 70 fixed on said shaft; two basket-supporting shafts rotatably supported on said arms; a basket for containing the candy cores to be dipped, fixed with relation to each of said last-mentioned shafts; a pinion and two studs 75 fixed on each of said basket-supporting shafts; a cam fixed with relation to the main frame, which cam has a peripheral rim, and a peripheral and a chordal channel; a rack-segment adapted to engage the teeth of the pinions on 80 said basket-supporting shafts; and means for rotating the main shaft to pass the candy cores beneath the surface of the liquid chocolate.

11. In a chocolate-dipping machine, in combination, a supporting-frame; a receptacle for the liquid chocolate; a main shaft rotatably mounted on said supporting-frame; two arms fixed on said main shaft; two basket-supporting shafts rotatably mounted on said arms; a 90 basket for containing the candy cores to be dipped, fixed with relation to each of said basket-supporting shafts; a pivoted vibrator-arm for each of said shafts, having connection with its shaft at one end; a vibrator-cam 95 for engaging the free ends of said vibrator-arms; and a cam fixed with relation to the supporting-frame, for raising said vibrator-arms from engagement with the vibrator-cam.

12. In a chocolate-dipping machine, in combination, a supporting-frame; a receptacle for the liquid chocolate; means for passing the candy cores to be dipped beneath the surface of the liquid chocolate; a vibrator-arm; a vibrator-cam for removing the excess of chocolate 105 from said cores; and a cam for withdrawing said vibrator-arm from engagement with the vibrator-cam.

13. In a chocolate-dipping machine, in combination, a supporting-frame; a receptacle for the liquid chocolate; an open receptacle for containing the candy cores to be dipped; means for passing the cores within said open receptacle beneath the surface of the liquid chocolate; a vibrator-arm having connection 115 with said open receptacle; a vibrator-cam for actuating said vibrator-arm; and a cam fixed with relation to said supporting-frame, for withdrawing the vibrator-arm from engagement with said vibrator-cam.

14. In a chocolate-dipping machine, in combination, a supporting-frame; a receptacle for the liquid chocolate; a main shaft rotatably mounted on said supporting-frame; a basket for containing the candy cores to be dipped, 125 supported by said main shaft; means for rotating said shaft and passing the cores within said basket beneath the surface of the liquid chocolate; a vibrator-arm having connection with said basket; a rotatable vibrator-cam for actuating said vibrator-arm; means for rotating said vibrator-cam; and a cam 130

fixed with relation to said supporting-frame, for withdrawing said vibrator-arm from engagement with said vibrator-cam.

15. In a chocolate-dipping machine, in combination, a supporting-frame; a receptacle for the liquid chocolate; an open receptacle for containing the candy cores to be dipped; a main shaft for passing the cores within said open receptacle beneath the surface of the liquid chocolate; a clutch; a clutch member for operating said clutch to start and stop the rotation of said main shaft; a stop-wheel; and a lever engaging said stop-wheel, for automatically disengaging said clutch and stopping the rotation of said main shaft at certain predetermined positions of the mechanism.

16. In a chocolate-dipping machine, in combination, a supporting-frame; a main shaft rotatably mounted on said frame; a receptacle for the liquid chocolate, fixed in said supporting-frame beneath said main shaft; two arms fixed on said main shaft; two basket-supporting shafts pivotally mounted on said arms; a basket for containing the candy cores to be dipped, fixed on each of said basket-supporting shafts, and adapted to be passed beneath the surface of the liquid chocolate by the rotation of said main shaft; means for rotating said main shaft; a clutch mechanism for starting and stopping the rotation of said main shaft; and a stop-wheel fixed on said main shaft, adapted to disengage said clutch mechanism, to stop the rotation of said main shaft.

35 17. In a chocolate-dipping machine, in combination, a supporting-frame; a main shaft rotatably mounted on said frame; a receptacle for the liquid chocolate, fixed in said supporting-frame beneath said main shaft; two arms fixed on said main shaft; two basket-supporting shafts pivotally mounted on said arms; a basket for containing the candy cores to be dipped, fixed on each of said basket-supporting shafts, and adapted to be passed beneath the surface of the liquid chocolate by the rotation of said main shaft; a pinion on each of said basket-supporting shafts; a cam fixed with relation to said supporting-frame; two studs projecting from each of said basket-supporting shafts, adapted to be engaged by the cam-surface of said cam; means for rotating said main shaft; a clutch mechanism for starting and stopping the rotation of said main shaft; a stop-wheel fixed on said main shaft, adapted to disengage said clutch mechanism to stop the rotation of said main shaft; a vibrator-arm for each of said basket-supporting shafts, having a pivotal connection with its said shaft; and a vibrator-cam for engaging the free ends of said vibrator-arms, to remove the excess of chocolate from said cores.

18. In a chocolate-dipping machine, in combination, a supporting-frame; a main shaft rotatably mounted on said frame; a receptacle for the liquid chocolate, fixed in said supporting-frame beneath said main shaft; two

arms fixed on said main shaft; two basket-supporting shafts pivotally mounted on said arms; a basket for containing the candy cores to be dipped, fixed on each of said basket-supporting shafts, and adapted to be passed beneath the surface of the liquid chocolate by the rotation of said main shaft; means for rotating said main shaft; a vibrator-arm for each of said basket-supporting shafts, having a pivotal connection with its said shaft; and a vibrator-cam for engaging the free ends of said vibrator-arms, for removing the excess of chocolate from said cores.

19. In a chocolate-dipping machine, in combination, a supporting-frame; a main shaft rotatably mounted on said frame; a receptacle for the liquid chocolate, fixed in said supporting-frame beneath said main shaft; two arms fixed on said main shaft; two basket-supporting shafts pivotally mounted on said arms; a basket for containing the candy cores to be dipped, fixed on each of said basket-supporting shafts, and adapted to be passed beneath the surface of the liquid chocolate by the rotation of said main shaft; means for rotating said main shaft; a vibrator-arm for each of said basket-supporting shafts, having a pivotal connection with its said shaft; a rotatable vibrator-cam adapted to engage the free ends of said vibrator-arms, for vibrating said baskets to remove the excess of chocolate from said cores; a clutch mechanism for starting and stopping the rotation of said main shaft; and a stop-wheel fixed on said main shaft, adapted to disengage said clutch mechanism to stop the rotation of said main shaft at certain predetermined positions of the mechanism.

20. A machine for coating pieces of material, comprising a receptacle containing the coating substance; a holding device containing the material to be coated; an operating mechanism for moving the holding device, adapted to carry said device by a continuous rotary motion through the coating substance; and a shaking mechanism traveling with the holding device so as to shake it laterally when it emerges from the coating substance.

21. A machine for coating pieces of material, comprising a receptacle containing the coating substance; a holding device containing the material to be coated; an operating mechanism for moving the holding device, adapted to carry said device by a continuous rotary motion through the coating substance; a shaking mechanism traveling with the holding device so as to shake it when it emerges from the coating substance; and an adjusting device for adjusting the shaking mechanism.

22. A machine for coating pieces of material, comprising a holding device for the material; a receptacle containing the coating substance; means for moving the holding device, adapted to carry said device by a continuous rotary motion through the substance in the receptacle; a shaking-arm traveling

with the holding device; and a rotating wheel provided with an uneven or toothed face adapted to engage said arm so as to operate it.

23. A machine for coating pieces of material, comprising a holding device for the material; a receptacle containing the coating substance; means for moving the holding device through the substance in the receptacle; a shaking-arm connected with the holding device; a rotating wheel provided with an uneven or toothed face adapted to engage said arm so as to operate it; and means for rendering said arm inoperative when in a predetermined position.

15 24. A machine for coating pieces of material, comprising a receptacle for the coating substance; a main shaft associated therewith and carrying one or more cross-arms; a second rotatable shaft mounted upon said cross-arms; a holding device for the material, connected with said second shaft by means of supporting-arms, so that the second shaft is free from the material in the receptacle; and means associated with said second shaft, for varying the position of the holding device as it moves around the main shaft.

25 25. A machine for coating pieces of material, comprising a receptacle for the coating substance; a main shaft associated therewith, and carrying one or more cross-arms; a second rotatable shaft mounted upon said cross-arms; a holding device for the material, connected with said second shaft by means of supporting-arms, so that the second shaft is free from the material in the receptacle; means associated with said second shaft, for varying the position of the holding device as it moves around the main shaft; and a shaking mechanism for reciprocating said second shaft so as to remove the surplus coating substance from the pieces of material.

30 26. A machine for coating pieces of material, comprising a receptacle for the coating substance; a main shaft associated therewith, and carrying one or more cross-arms; a second rotatable shaft mounted upon said cross-arms; a holding device for the material, connected with said second shaft by means of supporting-arms, so that the second shaft is free from the material in the receptacle; means associated with said second shaft, for varying the position of the holding device as it moves around the main shaft; a shaking-arm connected with said second shaft so as to reciprocate; and a rotating wheel provided with an uneven or toothed face, which engages said shaking-arm so as to operate the same.

35 27. A machine for coating pieces of material, comprising a receptacle for the coating substance; a main shaft associated therewith, and carrying one or more cross-arms; a second rotatable shaft mounted upon said cross-arms; a holding device for the material, connected with said second shaft by means of supporting-arms, so that the second shaft is free from the material in the receptacle;

means associated with said second shaft, for varying the position of the holding device as it moves around the main shaft; a shaking-arm connected with said second shaft so as to reciprocate; a rotating wheel provided with an uneven or toothed face, which engages said shaking-arm so as to operate the same; and a guide associated with said wheel, adapted to disengage the shaking-arm therefrom when the holding device reaches a predetermined position.

40 28. A machine for coating pieces of material, comprising a receptacle for the coating substance; a main shaft associated therewith, and carrying one or more cross-arms; a second rotatable shaft mounted upon said cross-arms; a holding device for the material, connected with said second shaft by means of supporting-arms so that the second shaft is free from the material in the receptacle; means associated with said second shaft, for varying the position of the holding device as it moves around the main shaft; a shaking mechanism for reciprocating said second shaft so as to remove the surplus coating substance from the pieces of material, said shaking mechanism comprising a pivoted arm connected with said shaft, a wheel mounted upon the main shaft, and provided with a roughened or toothed face adapted to engage said pivoted arm, and an adjusting device for adjusting the movement of the shaking mechanism.

45 29. A machine for coating pieces of material, comprising a holding device for the pieces of material; a receptacle for the coating substance; mechanism for moving said holding device through the coating substance; a guiding arm or arms associated with the holding device; and a guide-plate engaged thereby so as to vary the position of the holding device as it is moved by said moving mechanism.

50 30. A machine for coating pieces of material, comprising a receptacle for the coating substance; a main shaft mounted in proximity thereto; one or more holding devices for the material, connected with said main shaft so as to rotate therewith; a guiding-arm connected with each holding device; a guide-plate provided with guides engaged by the guiding-arm, and adapted to control the position of the holding device in a predetermined manner.

55 31. A machine for coating material, comprising a receptacle for the coating substance; a main shaft associated therewith; an auxiliary shaft connected to the main shaft so as to rotate therewith; a holding device connected with the auxiliary shaft so as to rotate therewith, and adapted to hold the material to be coated; a guiding arm or arms connected with said auxiliary shaft; a guide-plate provided with guides adapted to be engaged by said guiding arm or arms, so as to vary the position of the holding device in a predetermined manner.

60 32. A machine for coating material, comprising a receptacle for the coating substance;

- a main shaft associated therewith; an auxiliary shaft connected to the main shaft so as to rotate therewith; a holding device connected with the auxiliary shaft so as to rotate therewith, and adapted to hold the material to be coated; a guiding arm or arms connected with said auxiliary shaft; a guide-plate provided with guides adapted to be engaged by said guiding arm or arms, so as to vary the position of the holding device in a predetermined manner; a pinion connected with said auxiliary shaft; and a rack or segment gear adapted to engage the same when in a predetermined position, and rotate the auxiliary shaft so as to invert the holding device.
33. A machine for coating material, comprising a receptacle for the coating substance; a main shaft associated therewith; an auxiliary shaft connected to the main shaft so as to rotate therewith; a holding device connected with the auxiliary shaft so as to rotate therewith, and adapted to hold the material to be coated; a guiding arm or arms connected with said auxiliary shaft; a guide-plate provided with guides adapted to be engaged by said guiding arm or arms, so as to vary the position of the holding device in a predetermined manner; a pinion connected with said auxiliary shaft; a rack or segment gear adapted to engage the same when in a predetermined position, and rotate the auxiliary shaft so as to invert the holding device; and means for automatically stopping the main shaft when the holding device is inverted.
34. A machine for coating material, comprising a receptacle for the coating substance; a main shaft mounted in proximity thereto; a driving mechanism for said main shaft; an auxiliary rotatable shaft connected to the main shaft so as to rotate therewith; a holding device for the material to be coated, connected with said auxiliary shaft; a controlling mechanism for controlling the position of the holding device; and means for automatically stopping the driving mechanism of the main shaft when the holding device reaches a predetermined position.
35. A machine for coating pieces of material, comprising a receptacle for the coating substance; a main shaft mounted in proximity thereto; a driving mechanism for said main shaft; an auxiliary rotatable shaft connected to the main shaft so as to rotate therewith; a holding device for the material to be coated, connected with said auxiliary shaft; two guiding-arms rigidly connected with said auxiliary shaft; a guide-plate provided with guides engaged by the guiding-arms, said guides so positioned as to move the holding device to a horizontal position when it reaches a predetermined point; a plate adapted to be placed on top of the holding device; and means for inverting the holding device so as to deposit the coated pieces of material on said plate.
36. A machine for coating pieces of material, comprising a receptacle for the coating substance; a main shaft mounted in proximity thereto; an auxiliary shaft connected with the main shaft so as to rotate therewith; one or more supporting-arms connected with the auxiliary shaft and projecting therefrom; a holding device removably connected with said supporting arm or arms, and adapted to receive the material to be coated.
37. A machine for coating pieces of material, comprising a receptacle for the coating substance; a main shaft mounted in proximity thereto; an auxiliary shaft connected with the main shaft so as to rotate therewith; one or more supporting-arms connected with the auxiliary shaft and projecting therefrom; a holding device removably connected with said supporting arm or arms and adapted to receive the material to be coated; a plate adapted to be placed over the holding device; a holding-spring associated with each supporting-arm, for holding said plate in position; and a controlling-lever associated with the holding-spring.
38. A machine for coating pieces of material, comprising a receptacle for the coating substance; a main shaft associated therewith; an auxiliary shaft connected with the main shaft so as to rotate therewith; a holding device for the material to be coated, connected with the auxiliary shaft; two guiding-arms also connected with said auxiliary shaft; a guide-plate provided with a guide engaged by the two guiding-arms while the holding device is passing through the coating substance; a second guide on said guide-plate; and means for moving the guiding-arms when they reach a predetermined position so that one of them passes along the second guide, so as to vary the position of the holding device.
39. A machine for coating pieces of material, comprising a receptacle containing the coating substance; a holding device for containing the material to be coated; an operating mechanism for moving the holding device through the coating substance, and for turning the holding device into a substantially vertical position as it rises from the coating material; and a shaking mechanism adapted to shake the holding device when in such substantially vertical position.
40. In a machine for coating pieces of material, the combination with a stationary receptacle containing a coating substance, of a plurality of holding devices simultaneously carried in a substantially vertical plane by the machine and containing the material to be coated, and operating mechanism for successively carrying said holding devices beneath the surface of the coating substance.
41. In a machine for coating pieces of material, the combination with a stationary receptacle containing a coating substance, of a plurality of holding devices simultaneously carried by the machine and containing the material to be coated, operating mechanism

for successively carrying said holding devices beneath the surface of the coating substance, and shaking mechanism for successively horizontally vibrating said holding devices after 5 they emerge from the coating substance.

42. In a machine for coating pieces of material, the combination with a receptacle containing a coating substance, of a plurality of holding devices simultaneously carried by 10 the machine and each having a plurality of compartments containing material to be coated, operating mechanism for successively immersing said holding devices in the coating substance, shaking mechanism for successively 15 vibrating said holding devices after they emerge from the coating substance, and operative connections between said mechanisms whereby one holding device is carried through the coating substance while another 20 holding device is simultaneously vibrated to remove the excess of the coating substance.
43. In a machine for coating pieces of material, the combination with a receptacle con-

taining a coating substance, of a plurality of holding devices simultaneously carried by 25 the machine in a plane passing through said receptacle and containing the material to be coated, and operating mechanism for carrying one holding device through the coating substance and simultaneously vibrating another holding device to remove the excess of 30 the coating substance.

44. In a dipping-machine, the combination of a tank or receptacle, for containing the coating material, a plurality of orbitally-carried holders or dipping elements having a path of movement in a vertical plane and thereby having an automatic depression into said receptacle, and means for horizontally 35 vibrating said holders or dipping elements to 40 relieve the charges carried therein from a surplus of the coating material.
